UNITED STATES PATENT OFFICE.

ANDREW BENSON, OF CHICAGO, ILLINOIS, ASSIGNOR TO LEWIS E. CURTIS, OF CHICAGO, ILLINOIS.

MACHINE FOR CUTTING SHEET METAL.

No. 901,773.

Specification of Letters Patent.

Patented Oct. 20, 1908.

Application filed January 27, 1908. Serial No. 412,695.

To all whom it may concern:

Be it known that I, ANDREW BENSON, a citizen of the United States, residing in Chicago, in the county of Cook and State of Illinois, have invented a new and useful Improvement in Machines for Cutting Sheet Metal, of which the following is a specification.

In an accompanying application, Serial No. 412,694, I have described and claimed a process of cutting sheet metal, preparatory to expanding it, consisting in first slitting transverse sections or portions of the sheets with alined slits of uniform length and spaced to correspond to the width of the strands in the completed article, such slit portions being separated from each other by uncut bond portions whose width corresponds to the length of the bonds in the completed article, and then uniting the alternate slits of adjacent slitted sections by cutting through alternate bond portions.

The present invention is a machine adapted to slit sheet metal, its object being to enable the manufacture of expanded metal in accordance with the process rapidly and cheaply, and its nature is fully disclosed in the subjoined description and the accompanying drawing, and in the latter.

Figure 1 is a side elevation of the machine. Fig. 2 is a longitudinal vertical section. Fig. 3 is a transverse vertical section. Fig. 4 is a partial plan of the cutting roll which forms the long slits and Fig. 5 is a like view of the roll which cuts the bonds. Fig. 6 shows a plan of the metal after its rejection to the first pair of rolls and Fig. 6^a is an edge view of the same. Fig. 7 shows the mechanism for controlling the admission of the sheets to the cutting rolls. Fig. 8 is a section on line 8—8 of Fig. 2 of the guides for preventing lateral movement by the sheet while it is moving through the machine.

The machine embodies two pairs of slitting rolls, those marked 25 and 26 cutting the long slits, and those marked 27 and 28 making the slits in the bond portions of the sheets, the former operating in advance of the latter. They are supported on suitable frame work 10 and are actuated by a train of gears driven by the pulley 11. The shaft 12 of said pulley carries a pinion 13 meshing with a gear 14 on said shaft 15. Shaft

15 also carries a pinion 16 which meshes with and actuates a large gear 17 on shaft 18. On the opposite ends of shaft 18 are gears 19 and 20, of which gear 19 meshes with gears 21 and 22 on the ends of the lower slitting rolls 26 and 28 and gear 20 meshes with a gear 23 located above it and through the meshing of gear 23 with gear not shown on the end of the upper slitting roll 25 and with another gear (not shown) on the end of the other upper slitting roll 27; both said rolls are actuated in unison with the said lower rolls.

The sheets of metal to be slit are fed into the machine over table 29, and first enter between the rolls 25 and 26. These rolls 70 are provided with counteracting cutters 25^a notched at 25^b, as shown at Fig. 4, this construction causing the slitting of the sheet from edge to edge with slits such as are shown at 30 in Fig. 6, the slits being arranged in groups in the same transverse zones or sections of the sheet, and the different groups of slits being separated from each other by uncut zones or sections 31, forming the bonds in the completed article. 80 Adjacent to these rolls 25 and 26, are stripers 32, acting to strip the slit metal from the cutters should it tend to cling thereto. There are two series of these stripers and they are adapted to enter the 85 spaces between the cutters, one series between the cutters of the upper roll and the other series between the cutters of the lower roll.

After having the long slits formed in it, 90 the sheet moves from rolls 25 and 26 into the bite of rolls 27 and 28, which are fashioned as shown particularly at Figs. 2 and 5, that is to say, they are flattened as at 33, and between these flattened sides are arranged 95 cutters 34 adapted to sever the bonds 31. These severations are distributed as indicated in broken lines at Fig. 6, that is to say the slits through any one bond formed by one cutter 34 connect only alternate slits 100 30 on each side of that bond, and the next succeeding cutter acts on the following bond so as to connect therethrough the alternate slits not joined by the previous cutter.

Inasmuch as rollers 27 and 28 are not 105 adapted to feed the sheets as continuously as necessary, I provide feed rolls 35 and 36, which are located as shown and take hold of

the sheets shortly before or as soon as they leave rolls 27 and 28 and control them for the balance of the time they are in the machine. The lower one of these rolls is actuated by a chain 37 passing over a sprocket 38 on roll 28. By the aid of these rolls I insure the proper movement of the sheets after they have been released by rolls 25 and 26, so that the bonds at the tail end of the 10 sheets will be properly operated upon by rolls 27 and 28.

It is desirable, of course, that the rolls 25 and 26 should commence operating upon the sheets at a predetermined point thereon, and 15 hence I provide means for arresting the sheet as it enters, the arresting means being adapted to release the sheet at the proper time. These means consist of the fingers or stops 40, having their ends bent downward so as 20 to engage the advance edge of the sheet, and a rock shaft 41 upon which the fingers are mounted. Rock shaft 41 has an arm 42 riding on a cam ring 43 upon the roll 26 and provided with projections 44 at intervals 25 adapted to lift the arm 42 as the ring revolves. The projections are timed to cause the fingers to release the sheets at the proper times.

It is of course necessary that the sheets 30 being operated upon should not deviate laterally from a straight path after they enter the machine, because of the narrowness of the spaces between the cuts made by the first rolls and the danger that the cuts effected by 35 the second pair of rolls would not be properly located with reference to those made by the first pair if any deviation should occur. To guide the sheet and prevent any such deviation, I place just in advance of the 40 second pair of rolls a series of guides 45, the upper edges of which are thin and are arranged in line with the strands cut by the first rolls, and slightly above the bottom plane of the sheet, so that they will enter 45 between such of the strands in the sheet as may have been sprung down below the plane of the sheet by the cutters of the first rolls as seen at Fig. 6, so that the guides are enabled to resist any tendency by the sheet 50 to move laterally. By means of these guides I insure the making of the cuts by the second pair of rolls in proper relation to those made by the first pair of rolls. The guides are fitted upon a dovetail cross bar 45^a, which 55 is suitably secured in place.

It will be noted that the second pair of rolls are adapted to cut in alinement with the first pair of rolls, but the cutters of the second pair are divided into two groups, 60 each acting in slitting a different bond from the bond slit by the other group. In other words, the first group will slit one bond connecting alternate pairs of slits in the slitted sections adjoining that bond, and

the other group will act upon the second bond section in a similar manner, connecting only alternate pairs of slits of the slitted sections adjacent to said second bond section.

While the construction which I have shown is the best now known to me, it will 70 be understood I do not wish to be limited to the same, nor to the use of rotary slitting devices, as obviously other forms of slitting devices can be used, and other features of the invention be changed without departing 75 from the spirit or the letter of the claims.

I claim:

1. In a machine for slitting sheet metal preparatory to expanding it, the combination of slitting rolls for forming long alined 80 slits in transverse sections of the sheets, separated by transverse uncut bond sections, and slitting rolls for severing the bond sections so as to connect alternate pairs of slits in the slitted sections at opposite sides of the bond 85 sections.

2. In a machine for slitting sheet metal preparatory to expanding it, the combination of slitting rolls for forming alined longitudinal slits of uniform length in adjacent 90 transverse sections of the sheet, such sections being separated by uncut bond sections, and other slitting rolls for severing the bond sections in such manner as to connect only alternate pairs of slits in the slitted sections 95 through any one bond.

3. The combination of rolls for forming alined slits in transverse sections of the sheets and other rolls arranged in the rear of the first mentioned ones and acting to slit the 100 bonds between the slitted sections in such manner as to connect the alternate pairs of slits therein.

4. The combination of rolls for forming alined slits in transverse sections of the 105 sheets, other rolls arranged in the rear of the first mentioned ones and acting to slit the bonds between the slitted sections so as to connect alternate pairs of the slits made by the first rolls, essentially as described, and 110 means for feeding the sheet after it passes from the first mentioned rolls.

5. The combination of rolls for forming alined slits in transverse sections of the sheets, other rolls arranged in the rear of the 115 first mentioned ones and acting to slit the bonds between the slitted sections in such manner as to connect alternate pairs of the slits made by the first rolls essentially as described, and guides for preventing lateral 120 movement by the sheets.

6. The combination of rolls for forming alined slits in transverse sections of the sheets, other rolls arranged in the rear of the first mentioned ones and acting to slit the 125 bonds between the slitted sections in such manner as to connect alternate pairs of slits made by the first rolls and guides for pre-

venting lateral movement by the sheets, such guides engaging the slitted portions of the sheet.

7. In a machine for slitting metal sheets preparatory to expanding them, the combination with means for forming long alined slits in transverse sections of the sheets, of means for severing the bonds between such sections so as to connect alternate pairs of slits through alternate bonds.

8. In a machine for slitting metal sheets preparatory to expanding them, the combination with means for forming long alined slits in transverse sections of the sheets, of means for severing the bonds between the sections so as to connect alternate pairs of slits through alternate bonds, and guides for preventing lateral movement by the sheets engaging the slitted portions thereof.

9. In a machine for slitting sheet metal preparatory to expanding it, the combination with means for forming alined slits in

separated transverse sections of the sheets, of means for severing the separating parts of the sheets in such manner as to connect one half of said slits through each separating portion in successive order.

10. In a machine for slitting sheet metal preparatory to expanding it, the combination with means for forming alined slits in separated transverse sections of the sheets, of means for severing the separating parts of the sheet in such manner that one half of said slits will be connected through one of said separating portions, and the other half of said slits be connected through the next separating portion, said means for severing the separating portions of the sheet consisting of cutters mounted upon the same shaft.
